AQUARIUM FILTER

Jerry L. Malis, Wyndmoor, Pa.

Application October 14, 1955, Serial No. 38,375

Term of patent 14 years

(Cl. D91—2)

Fig. 2.

Fig. 1.

Fig. 3.

Fig. 4.

Fig. 5.

Figure 1 is a perspective view of the top side of an aquarium filter showing my new design;

Figure 2 is a perspective view of the bottom side of the filter;

Figure 3 is an end elevational view thereof;

Figure 4 is a sectional view as taken along the line 4—4 of Figure 1; and

Figure 5 is a sectional view as taken along the line 5—5 of Figure 1.

I claim:

The ornamental design for an aquarium filter, substantially as shown.
